CLAIM

The ornamental design for a floor washer, as shown and described.

DESCRIPTION

FIG. 1 is a perspective view of a floor washer, showing our new design;

FIG. 2 is a front view of the floor washer depicted in FIG. 1;

FIG. 3 is a back view of the floor washer depicted in FIG. 1;

FIG. 4 is a left side view of the floor washer depicted in FIG. 1;

FIG. 5 is a right side view of the floor washer depicted in FIG. 1;

FIG. 6 is a top view of the floor washer depicted in FIG. 1;

FIG. 7 is a bottom view of the floor washer depicted in FIG. 1; and,

FIG. 8 is an enlarged view of a portion of the floor washer depicted in FIG. 1.

The evenly broken lines depict various portions of the floor washer that form no part of the claimed design. The dot-dash broken lines circumscribe the enlarged detail and form no part thereof.
